RUG DISPLAYING AND REMOVING MECHANISM

Application filed May 7, 1929. Serial No. 361,216.

This invention relates to a rug displaying and removing mechanism and has for its primary object to provide, in a manner as hereinafter set forth, a convenient and expeditious means for displaying each rug of a pile of rugs and for selectively removing the rugs from the pile.

A further object of the invention is to provide a device for the purpose aforesaid whereby the physical effort ordinarily necessary to display a pile of rugs is largely eliminated, thereby making it possible for saleswomen to display rugs with substantially the same degree of ease and efficacy as salesmen.

15 A further object of the invention is to eliminate the likelihood of a pile of rugs becoming disarranged by the frequent handling thereof, thereby preventing the pile from becoming unsightly and unworkable and maintaining the rugs in a neat and orderly arrangement.

20 A further object of the invention is to facilitate the removal of a selected rug from a pile without disarranging the remaining rugs and without the expenditure of any appreciable amount of physical effort.

25 A further object of the invention is to enable a pile of rugs to be displayed in a relatively short period of time, thereby conserving the time of the customer and salesman and making possible a greater number of sales in one day.

With the foregoing and other objects in view, the invention consists of the novel construction, combination and arrangement of parts as hereinafter more particularly described, and as illustrated in the accompanying drawings wherein is shown an embodiment of the invention, but it is to be understood that such description and drawings are to be taken illustrative and that the invention is intended to be limited only by the scope of the claims hereunto appended.

45 In the accompanying drawings in which like numerals are employed to designate like parts throughout the same:

Figure 1 is a top plan of a device in accordance with this invention.

50 Figure 2 is a side elevation thereof.

Figure 3 is a transverse section therethrough.

Figure 4 is a side elevation of the device showing the positions of the arms at the completion of the display of a pile of rugs.

55

Figure 5 is a longitudinal section through one of the forward arms.

Figure 6 is a fragmentary longitudinal section through one of the rearward arms.

Figure 7 is a fragmentary plan of a forward 60 and rearward arm assembled on their common shaft.

Figure 8 is a section taken on line 8—8 of Figure 5.

Figure 9 is a perspective view of a forward 65 arm extension and associated parts.

Figure 10 is a perspective view of one of the movable fingers carried by each forward arm extension.

Figure 11 is a perspective view of the other 70 movable finger of each forward arm extension.

Figure 12 is a perspective view of a rearward arm extension and associated parts.

Figure 13 is a perspective view of a movable finger carried by each rearward arm extension.

Figure 14 is a fragmentary perspective view of a forward arm and extension therefor.

80

Figure 15 is a fragmentary top plan of the embodiment shown in Figure 9.

Figure 16 is a perspective view of one of the rods which are secured to the forward ends of the rugs in the pile.

85

Figure 17 is a perspective view of one of the clamps for securing the rods in position.

Figure 18 is a sectional elevation showing the assembled relation of a rug, rod and clamp.

90

Figures 19, 20, 21 and 22 are diagrammatic views showing the various stages in the operation of removing a rug from the pile.

Figure 23 is a fragmentary perspective view of one of the runners which are inserted 95 between certain of the rugs during the removal operation.

Referring to the drawings in detail, the numeral 1 designates a base for the reception thereon of a pile of rugs 2 in superposed rela-

100

tion. The base 1 is preferably of a size to extend beyond the ends and sides of a 9 x 12 rug when the latter is positioned thereon. Secured to the sides of the base 1 and extending upwardly therefrom is a pair of uprights 3 and 4. Extending through the sides of the base and through the uprights 3 and 4 is a shaft 5, upon the extreme outer ends of which is fixedly mounted a pair of forwardly extending arms 6 and 7. Rotatably mounted on the shaft 5, between the arms 6 and 7 and the sides of the base, is a pair of rearwardly extending arms 8 and 9. Connecting the forward arm 6 with the rearward arm 8 is a cable 10, which extends downwardly from the forward arm 6 over a pulley 11 secured to the base 1, thence upwardly and rearwardly over a pulley 12 secured to the upright 3, from where the cable extends downwardly and rearwardly to the rearward arm 8.

The forward arm 7 is connected with the rearward arm 9 in a similar manner by means of a cable 13. Mounted on the forward arm 6 and projecting therefrom at an upward inclination is an actuating lever 14 by means of which the forward and rearward arms may be swung in a vertical arc towards each other due to the operation of the cables 10 and 13.

The arm 6 is of cylindrical formation and may be conveniently secured to the shaft 5 by means of a pin 14 extending through the shaft and a collar 15 which forms a part of the arm 6. The arm 6 is provided at its forward end with a cap 17 through which extends an extension 18 which is of I-beam construction with the flanges thereof disposed vertically. Fixedly secured to the inner end of the extension 18 is a piston 19, which is provided with a peripherally extending row of ball bearings 20 for engagement with the inner face of the cylindrical member 6. Interposed between the rearward end of the member 6 and the piston 19 is a coiled spring 21, the compression of which normally forces the extension 18 in a forward direction. The forward arm 7 is constructed in the same manner as the forward arm 6 and is provided with an extension 22 corresponding to the extension 18.

The rearward arm 8 is rotatably supported on the shaft 5 by means of a suitable bearing 23 and projecting from the rearward end of the arm 8 is an extension 24 which is normally forced in a rearward direction by means of a coiled spring 25 disposed within the cylindrical arm 8. The extension 24 is of I-beam construction and is so positioned that the flanges thereof are disposed horizontally. The rearward arm 9 is of the same construction as the arm 8 and is provided with an extension 26 corresponding to the extension 24.

Slidably secured to the inner flange 27 of the extension 18, by means of a pair of clamps 28, is what will be termed an upper finger 29, the forward portion of which projects above

the flange 27 and terminates at its forward extremity in a nose 30. Slidably secured to the outer flange 31 of the extension 18, by means of a pair of clamps 32, is what will be termed a lower finger 33 which is provided at its forward extremity with a nose 34. The inner flange 27 is of greater height than the outer flange 31 and the upper face of the nose 34 is projected above the upper face of the flange 31 into horizontal alignment with the upper face of the flange 27. The extension 22 is provided with an upper finger 35 and a lower finger 36 which correspond in every respect to the fingers 29 and 33 respectively.

The extension 24 of the rearward arm 8 has its upper flange 37 projecting beyond the remaining portion of the extension to provide a stationary upper finger 38. Slidably secured to the lower flange 39 of the extension 24, by means of suitable clamps 40, is a lower finger 41, the outer portion of which forms a counterpart of the finger 38 when such outer portion is projected from the end of the flange 39. The finger 41 is normally maintained in projected relation with respect to the flange 39 by means of a coiled spring 42. The extension 26 of the rearward arm 9 is provided with stationary and movable fingers corresponding to the fingers 38 and 41.

The lower finger 33 of the extension 18 is normally maintained with its outer end flush with the outer end of the extension by means of a coiled spring 43, in which position the nose 34 projects forwardly from the outer end of the extension. The lower finger 36 of the extension 22 is controlled by a spring 44 which corresponds to the spring 43. The upper finger 29 is normally maintained with its forward end flush with the forward end of the extension 18 by means of a cable 45 which is secured as indicated at 29' to the finger 29 and passes around the forward end thereof over a pulley 46 mounted at the forward end of the extension 18, and extends rearwardly beneath the shaft 5 between the collar 15 and bearing 23. The cable 45 then passes through an opening 8' into the rearward arm 8 and is secured at its rearward end as indicated at 24' to the extension 24 of the rearward arm 8.

The operation of the spring 25 in normally forcing the extension 24 in a rearward direction also controls the cable 45 whereby the finger 29 is normally maintained in its forward position. A similar cable 47 connects the upper finger 35 of the extension 22 with the extension 26 of the rearward arm 9. Connected with the upper finger 29 is a cable 48 which extends rearwardly and passes over a pulley 49 on the upright 3 and is secured to a handle member 50. Connected with the upper finger 35 is a cable 51 which extends rearwardly, thence transversely of the base and is passed over a pulley 52 on the upright

3 and is secured to the handle member 50. The handle member 50 operates in a vertically disposed slot 53 formed in the upright 3 and is adapted for selective engagement 5 with a series of teeth 54 disposed on either side of the slot 53.

Connected with the lower finger 33 is a cable 55 which passes over a pulley 56 and through a keeper 57 secured to the upright 10 member 3 and is secured to a ring 58 whereby the cable is prevented from becoming withdrawn through the keeper 57. A similar cable 59 is connected with the lower finger 36, which extends rearwardly, hence transversely of the base and passes over the pulley 56 and through the keeper 47 and is connected with the ring 58. Connected with the movable finger 41 of the extension 24 is a cable 60 which passes over a pulley 61 and 20 through a keeper 62 on the upright member 3 and is secured to a ring 63 whereby the cable 60 is prevented from being withdrawn through the keeper 62. A similar cable 64 is connected with the movable finger of the extension 26 and passes forwardly, thence transversely of the base, over the pulley 61 and through the keeper 62 and is connected with the ring 63.

Connected with the extension 18 is a cable 30 65, the rearward end of which passes through an opening in the arm 6 and is connected to a pedal 66 which is pivotally mounted in any suitable manner adjacent the upright member 3. A similar cable 67 is connected with 35 the extension 22 and extends therefrom to the pedal 66.

Connected to each side of the base 1, adjacent the forward end thereof, is a guide 68 for a plurality of rods 69. Each rod 69 is 40 adapted to be detachably secured to a rug, adjacent the forward edge of the latter, by means of clamps 70. The opposing legs of each clamp 70 are provided with oppositely disposed arcs 71 and 72 for respectively seating the rod 69 and a portion of the rug which is pressed outwardly by the action of the rod. The rods are of a length to extend beyond the side edges of the rug and spaced from each end thereof, each rod is provided with 50 a spacing washer 73, by means of which the rods are maintained in spaced relation.

Projecting inwardly from the inner face of each of the uprights 3 and 4 is a pair of spaced guide members 74. Slidably extending 55 through each pair of guides 74 is a bar 75, the lower portion of which is formed with teeth 76 to provide a rack. Meshing with the teeth 76 of each bar 75 is a gear 77 which is fixedly secured on a shaft 78 extending transversely 60 of the base 1. Adjacent the upright 3, a ratchet 79 is fixedly secured to the shaft 78 and disposed above the ratchet 79 is a horizontally disposed guide 80 which is supported by the upright 3. Operating within the guide 65 80 is a ratchet lever 81 to provide for the ac-

tuation of the shaft 78 and gears 77 through the medium of the ratchet 79.

Projecting upwardly from the base 1, between the rearward end thereof and each bar 75, is a guide 82 through which a rack bar 83 slidably extends. Meshing with the teeth of each rack bar 83 is a gear 84 which is fixedly secured to a shaft 85 extending transversely of the base. In alignment with the ratchet 79, longitudinally of the base, the shaft 85 is provided with a ratchet similar to the ratchet 79 and such ratchet is actuated by a ratchet lever 86 which extends upwardly through a horizontally disposed guide 87 projecting rearwardly from a guide 82.

Connecting the rack bars 75 is a cross bar 88 which extends across the pile of rugs in contact with the uppermost rug of such pile. Between the cross bar 88 and the upper ends of the rack bars 75, the latter are connected by means of a cross bar 89. The cross bars 88 and 89 are adapted for adjustment longitudinally of the rack bars 75, as by means of a series of spaced openings 90 extending through the rack bars 75. Adapted for suspension 90 from the upper cross bar 89, by means of 95 their hook-like upper ends, is a plurality of hook members 91.

In the operation of my device, a pile of rugs 2 is positioned on the base 1 and the cross bar 88 is adjusted longitudinally of the rack bars 75 to bear against the upper face of the uppermost rug of the pile 2. One of the rods 69 is secured to the forward end of each rug in the pile, by means of clamps 70 and the ends of the rods 69 are positioned within the guides 68. The lever 14 is then actuated to lower the forward arms 6 and 7 until the lower fingers 33 and 36 are seated on the uppermost of the rods 69. The fingers 33 and 36 are then withdrawn by exerting a pull on the ring 58 with which the cables 55 and 59 are connected, which permits a further lowering of the arms 6 and 7 until the noses 30 of the upper fingers 29 and 35 rest on the uppermost of the rods 69.

The ring 58 is then released and the fingers 33 and 36 respectively are actuated by the springs 43 and 44 to move in a forward direction whereby the noses 34 are passed under the uppermost of the rods 69. The lever 14 is then actuated to swing the arms 6 and 7 in a vertical arc. Due to the connection of the arms 6 and 7 with the rearward arms 8 and 9 respectively by the cables 10 and 13, the rearward arms 8 and 9 are swung in a vertical arc co-incidently with the swinging of the forward arms 6 and 7 and the paths of the rearward arms and forward arms are towards each other. At the upper end of the paths of movement of the arms the outer ends of the extensions 24 and 26 are disposed beneath the horizontal plane of the outer ends of the extensions 18 and 22. The extensions 18 and 22 are then drawn farther 125 130

into the cylindrical portions of the arms 6 and 7 by manipulation of the pedal 66 and the rod 69 which has been carried upwardly by the fingers on the extensions 18 and 22 is thereby transferred to the fingers 38 and 41 on the rearward extensions 24 and 26.

Before releasing the pedal 66, the lever 14 is actuated to start the return of the forward and rearward arms to their original positions. During the return movement of the arms, the rod 69 which has been transferred to the fingers 38 and 41 is carried by the latter and the rug to which the rod is secured is thereby folded upon itself.

By repeating the above explained operation, the next rug in the pile may be folded upon itself but before the lever 14 is actuated to start the upward movement of the arms, a pull is exerted on the ring 63 whereby the lower fingers 41 on the extensions 24 and 26 are removed from underneath the rod 69 secured to the rug which has just been folded upon itself. As illustrated in Figure 4, the folded portion of each successive rug becomes shorter, therefore as the operation progresses, it is necessary to shorten the distances between the fingers 29 and 35 and the shaft 5 and also between the fingers 38 and 41 and the shaft 5, before the transfer of each succeeding rod 69 from the fingers 29 and 35 to the fingers 38.

This may be accomplished by adjusting the handle member 50 with respect to the teeth 54 along the sides of the slot 53 through the upright member 3. As the handle member 50 moves upwardly, the fingers 29 and 35 are drawn towards the shaft 5 due to the cables 48 and 51 which connect the handle member 50 with the fingers 29 and 35. Upon the withdrawal of the fingers 29 and 35 towards the shaft 5, the extensions 24 and 26 are also drawn towards the shaft 5, due to their connection with the fingers 29 and 35 by means of the cables 45 and 47. Owing to the difference in height in the flanges 27 and 31 of the extension 18 and of the corresponding flanges of the extension 22, the ends of the rod 69 which is engaged by the fingers 29 and 35 will ride over the clamps 32 which secure the lower fingers 33 and 36 in position, when the fingers 29 and 35 are withdrawn towards the shaft 5. During the foregoing operation, the cross bar 89 is disconnected from the rock bars 75.

When it is desired to remove a rug from the pile, the rugs disposed above the rug selected for removal are folded over as above explained and the cross bar 89 with the hooks 91 suspended therefrom is secured in position. The cross bar 89 is adjusted longitudinally of the rack bars 75 to permit the lower end portions of the hook members to be inserted between the selected rug and that rug next above. The rack bars 75 are then moved upwardly by the actuation of the ratchet

lever 81 until the folded rugs assume substantially the position illustrated in Figure 20. A series of runners 92 are then inserted between the selected rug and the rugs which have been partially removed therefrom.

Each runner 92 is of elongated form and has secured to its side edges a series of spaced plates 93 which project above and below the upper and lower faces of the runners. The plates 93 on opposite edges of the runners are disposed in opposed relation and rotatably mounted between the upper ends of opposing plates as well as between the lower ends thereof are rollers 94.

The rollers 94 permit the runners 92 to be readily inserted between the selected rug and those rugs of the pile which have been partially removed from the selected rug. After the runners 92 have been inserted in position, a lifting bar 95 is passed thereunder, adjacent the rack bars 75. A cable or the like in the form of a loop 96 is then passed over the outer end of the bar 95 and each of the cables 96 is suspended from a hook 97, one of which is provided on each of the rack bars 75.

After the lifting bar 95 has been secured in position, a similar lifting bar 98 is passed under the runners 92 adjacent the rearward rack bars 83. The lifting bar 98 is suspended by means of cables 99 from the rack bars 83 similarly to the suspension of the lifting bar 95 from the rack bars 75. The rack bars 83 are then actuated upwardly to a position substantially as illustrated in Figure 22. The rack bars 75 and 83 slightly incline upwardly and rearwardly in order to permit the elevation of the forward portion of the folded rug before the rearward portion thereof without disturbing the position of the rearward portions of the folded rugs with respect to the rear edges of the rugs remaining flatwise on the pile.

It is thought that the many advantages of a rug displaying and removing mechanism in accordance with this invention will be readily apparent, and although the preferred embodiment of the invention is as illustrated and described, it is to be understood that various changes in the size, shape and arrangement of parts may be made, so long as such changes fall within the scope of the invention as defined in the appended claims.

What I claim is:

1. In a device of the character described, a pair of arms for pivotal mounting on a common axis, means operatively connecting the arms to provide for relative, reciprocating, swinging movement thereof, and means transferable from one arm to the other for engagement with a marginal portion of a rug.

2. In a device of the character described, a shaft, a pair of forward arms fixedly mounted on the shaft, a pair of rearward arms pivotally mounted on the shaft, means operative-

ly connecting the forward arms with the rearward arms to provide for relative, reciprocating, swinging movement thereof, and means transferable from one pair of said arms to the other for engagement with a marginal portion of a rug.

3. In a device of the character described, a shaft, a pair of forward arms fixedly mounted on the shaft, a pair of rearward arms pivotally mounted on the shaft, means operatively connecting the forward arms with the rearward arms to provide for relative, reciprocating, swinging movement thereof, and means carried by the forward arms for engagement with a marginal portion of a rug during the movement of the forward and rearward arms towards each other, said means being transferable to the rearward arms to be carried thereby during the movement of the forward and rearward arms away from each other.

4. In a device of the character described, a shaft, a pair of forward arms oppositely disposed with respect to a pile of rugs and fixedly mounted on said shaft, a pair of rearward arms oppositely disposed with respect to the pile of rugs and pivotally mounted on said shaft, a rod for connection with a marginal portion of a rug, means operatively connecting the forward arms with the rearward arms to provide for relative, reciprocating, swinging movement thereof, means carried by the forward arms for engagement with said rod during the movement of the forward and rearward arms towards each other, means for transferring said rod to the rearward arms for engagement with said rod during the movement of the forward and rearward arms away from each other.

5. In a device of the character described, a shaft, a pair of forward arms oppositely disposed with respect to a pile of rugs and fixedly mounted on the shaft, a pair of rearward arms oppositely disposed with respect to the pile of rugs and pivotally mounted on the shaft, means operatively connecting the forward and rearward arms to provide for relative, reciprocating, swinging movement thereof, a longitudinally movable extension forming a part of each arm, a rod for connection with a marginal portion of the uppermost rug of said pile of rugs, means carried by the extensions on the forward arms for engagement with said rod during the movement of the forward and rearward arms towards each other, means for transferring said rod to the extensions on the rearward arms at the end of the movement of the forward and rearward arms towards each other, and means carried by the extensions on the rearward arms for engagement with said rod during the travel of the for-

ward and rearward arms away from each other.

6. In a device of the character described, a shaft, a pair of forward arms oppositely disposed with respect to a pile of rugs and fixedly mounted on the shaft, a pair of rearward arms oppositely disposed with respect to the pile of rugs and pivotally mounted on the shaft, means operatively connecting the forward and rearward arms to provide for relative, reciprocating, swinging movement thereof, a longitudinally movable extension forming a part of each arm, a rod for connection with a marginal portion of the uppermost rug of said pile of rugs, a pair of longitudinally movable fingers carried by each forward extension for engagement with said rod during the movement of the forward and rearward arms towards each other, a stationary and a longitudinally movable finger carried by each rearward extension for engagement with said rod during the travel of the forward and rearward arms away from each other, and means for transferring said rod from the forward extensions to the rearward extensions at the end of the path of movement of the forward and rearward arms toward each other.

7. In a device of the character described, a pair of arms for pivotal mounting on a common axis, means operatively connecting the arms to provide for relative, reciprocating, swinging movement thereof, and means transferable from one arm to the other for engagement with a marginal portion of a rug, said last named means including a rod for disposition transversely of the rug to project beyond the side edges of the latter, and a plurality of clamps, each having a pair of legs for the reception of said marginal portion therebetween, the legs of each clamp having oppositely disposed, outwardly arched portions to provide a seat for the rod and for a surface portion of the rug.

8. In a device of the character described, a base for supporting a pile of rugs in superposed relation, a plurality of rods for engagement with marginal portions of the rugs at one end of the pile, and means pivotally connected with the base for consecutive engagement with the rods for successively shifting the rugs into folded position to expose the uppermost of the remaining rugs.

9. In a device of the character described, a base for supporting a pile of rugs in superposed relation, a plurality of rods for engagement with marginal portions of the rugs at one end of the pile, and spring controlled, adjustable means pivotally connected to the base for consecutive engagement with the rods for successively shifting the rugs into folded position to expose the uppermost of the remaining rugs.

10. In a device of the character described, a base for supporting a pile of rugs in super-

- posed relation, a plurality of rods for engagement with marginal portions of the rugs at one end of the pile, means pivotally connected to the base for consecutive engagement with the rods for successively shifting the rugs into folded position to expose the uppermost of the remaining rugs, upwardly movable racks supported by the base on opposite sides and intermediate the ends thereof, a cross bar connecting said racks and adjustable longitudinally thereof, and hook members for suspension from the cross bar for insertion beneath the lowermost of the shifted rugs.
11. In a device of the character described, a shaft, a pair of forward arms oppositely disposed with respect to a pile of superposed rugs and fixedly mounted on said shaft, a pair of rearward arms oppositely disposed with respect to the pile of rugs and pivotally mounted on said shaft, a plurality of rods disposed in superposed relation and each connected with a rug of said pile of rugs, a longitudinally movable extension carried by each arm, a longitudinally movable finger carried by each forward extension for engagement with the uppermost of said rods, means operatively connecting the forward and rearward arms to provide for relative, reciprocating, swinging movement thereof, a stationary and a longitudinally movable finger carried by each rearward extension, means for adjusting the position of the finger on the forward extension with respect to the shaft, means for normally maintaining the fingers upon the rearward extension nearer to said shaft than the finger on the forward extension, and means for actuating the forward extension to move the finger carried by the latter into closer proximity to the shaft than the fingers on the rearward extension.
12. In a device of the character described, a base for supporting a pile of rugs in superposed relation, a plurality of rods for engagement with marginal portions of the rugs at one end of the pile, means pivotally connected to the base for consecutive engagement with the rods for successively shifting the rugs into folded position to expose the uppermost of the remaining rugs, upwardly movable racks supported by the base on opposite sides and intermediate the ends thereof, a cross bar connecting said racks and adjustable longitudinally thereof, hook members for suspension from the cross bar for insertion beneath the lowermost of the shifted rugs, means for shifting the racks in an upward direction, a pair of racks positioned rearwardly of the first named racks, means for anchoring said lowermost rug to said last named racks, and means for shifting the latter in an upward direction.
13. In a device of the character described, a pair of arms, means to provide a common axis for pivotally mounting the arms, means

operatively connecting the arms to provide for relative, reciprocating, swinging movement thereof, and means transferable from one arm to the other for engagement with a marginal portion of a rug.

14. In a device of the character described, a pair of arms, means to provide a pivotal mounting for each arm, means operatively connecting the arms to provide for relative, reciprocating, swinging movement thereof, and means transferable from one arm to the other for engagement with a marginal portion of a rug.

15. In a device of the character described, a pair of forward arms, a pair of rearward arms, means to provide a pivotal mounting for each pair of arms, means operatively connecting the forward arms with the rearward arms to provide for relative, reciprocating, swinging movement thereof, and means transferable from one pair of said arms to the other for engagement with a marginal portion of a rug.

16. In a device of the character described, a pair of arms, means to provide a common axis for pivotally mounting the arms, means operatively connecting the arms to provide for relative, reciprocating, swinging movement thereof, and means transferable from one arm to the other for engagement with a marginal portion of a rug, said last named means including a rod for disposition transversely of the rug to project beyond the side edges of the latter, and a plurality of clamps, each having a pair of legs for the reception of the rod and a marginal portion of the rug therebetween.

In testimony whereof, I affix my signature hereto.

FRANK P. GRACEY.
